UNITED STATES PATENT OFFICE.

HARRY J. SWEANY, OF QUAPAW, OKLAHOMA.

FRAUD-PREVENTIVE FOR COIN-CONTROLLED VENDING-MACHINES.

1,128,385.

Specification of Letters Patent. Patented Feb. 16, 1915.

Application filed January 21, 1914. Serial No. 813,516.

To all whom it may concern:

Be it known that I, HARRY J. SWEANY, a citizen of the United States, residing at Quapaw, in the county of Ottawa and State of Oklahoma, have invented certain new and useful Improvements in Fraud-Preventives for Coin-Controlled Vending-Machines; and I do hereby declare the following to be a full, clear, and exact description of the invention, such as will enable others skilled in the art to which it appertains to make and use the same.

The primary object of this invention is to provide extremely simple and highly efficient means for protecting coin controlled vending machines against operation by spurious coins, slugs, checks, and in fact any object except a legal coin of the proper value.

Another object of the invention is to provide in a device of this nature a system of chutes which will return all objects except coins of the proper size and value to the depositor.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is a fragmentary vertical sectional view through a coin controlled vending machine, showing a portion of my fraud preventive device partly in elevation and partly in section, Fig. 2 is a view taken on the plane of line 2—2 of Fig. 1, Fig. 3 is a detail top plan view of the tilting platform and slide therefor, Fig. 4 is a longitudinal sectional view through the tilting platform taken on the plane of line 4—4 of Fig. 3, Fig. 5 is a horizontal sectional view taken on the plane of line 5—5 of Fig. 2, Fig. 6 is a transverse sectional view through the initial coin guideway taken on the plane of line 6—6 of Fig. 2, and showing the inclination of the guideway to a vertical plane, Fig. 7 is a view taken on the plane of line 7—7 of Fig. 2, and Fig. 8 is a sectional view through the coin guide which finally receives the proper coin and sets the machine into operation.

Referring to the drawings, 1 designates

the portion of a casing of a coin controlled vending machine having a coin entrance slot 2.

3 designates a coin guideway or chute which receives all coins of proper value inserted in the opening 2 and directs them into engagement with contact plates 4 and 5 whereby a circuit is closed to set the vending machine into operation. When the operation of the machine begins, the rod 6 actuates the pivoted contact plate 5 to allow the coin to drop into a money drawer or other receptacle 7.

The foregoing illustrates one form of vending machine which may be protected against fraudulent operation by my fraud preventing device to be now described, but it will be understood that this device may also be used in connection with vending machines of other types.

Coming now to the means which I employ for preventing other than coins of proper size and value entering the chute 3; 8 designates an inclined coin guideway in communication at its upper end with the inner terminal of the slot 2. This guideway is formed by a plate bent to provide a main or side wall 9, top and bottom walls 10 and 11, respectively and retaining flanges 12 and 13, 85 projecting toward each other from the free edges of the top and bottom walls and lying in a plane parallel to the plane of the side or rear wall 9. The guideway 8 is inclined to a vertical plane, as illustrated by Fig. 6, 90 so that a coin passing therewith, bears against the flanges 12 and 13. The top flange 12 is cut away for a portion of its width, as indicated by the numeral 14, so that when a coin of less than the proper diameter reaches the cut away portion, it will fall from the coin guide into a chute 15. This chute is one branch of a system of chutes which return all articles, except coins of the proper size and denomination, that 100 are inserted in the slot 2, to the depositor.

A pair of levers 16 and 17 are pivoted intermediate their ends to the guideway 8, have their lower ends curved to form coin supporting jaws, and are connected at their upper ends by means of the links 18 and stem 19 to a vertical plunger 20. Referring to Fig. 7, it will be seen that the lever 17 is pivoted to an ear 21 and is formed with a central offset portion 17' which receives the 110 coin guide 8 and permits the terminals of the lever being positioned in the central lon-

gitudinal plane of the guide. The lever 16 is pivoted to an ear 22 formed upon the ends of the guideway 8 and, as shown in Fig. 5, this lever is directly in line with the end of the guideway.

5 The plunger 20 works through an opening 23 formed in the top of the casing 1, is held normally in elevated position by means of the spring 24 and is formed adjacent its lower end with the transverse openings 25 and 26. A kicker lever 27 is pivoted intermediate its end, as indicated by the numeral 28, and swings in a vertical plane extending at right angles to the guideway 8 and 10 passing centrally between the levers 16 and 17. The upper end of the kicker lever extends angularly toward the levers 16 and 17 as indicated by the numeral 29 and a rounded lug 30 is formed upon one side of 15 the lever 27 between the pivot point 28 and the angular portion 29. This lug is received within the opening 25 when the plunger 20 is elevated and is received in the opening 26 when the plunger is forced inwardly. A 20 discharge chute 31 has a mouth 32 opening directly under the levers 16 and 17 and said chute connects with the main discharge chute 32 by means of an inclined chute 33. A slide 34 extends laterally and downwardly 25 from the upper terminal of the chute 31 in a direction opposite to the lever 27 and overlaps a tilting platform 35. This platform is mounted to swing about a pivot 36 supported in any suitable manner, such as by 30 the arm 37, and is held normally against the underside of the slide 34 by a weight 38 connected to the arm 39. A plurality of 35 burs 40 are formed upon the upper face of the platform 35, for a purpose to be herein- 40 after explained, and said platform is also provided with a rim or stop flange 41. The chute or coin guide 3 is positioned directly under the pivot 36 so that all coins which slide from the platform 35 when the latter 45 is in a vertical plane, drop into the chute, setting the vending machine into operation. The upper end of the chute 33 terminates to one side of and slightly above the upper end of the chute 3 to receive coins, disks et 50 cetera which slide from the platform 35 before the latter reaches a vertical plane.

55 42 indicates a permanent magnet designed to cause slugs, disks and other articles of a paramagnetic substance to be started from the platform 35 so as to slide into the chute 33.

43 indicates a guard plate positioned above the slide 34 so that coins knocked from between the jaws of the levers 16 and 17 by 60 the kicker lever 27 will fall properly upon the slide 34.

Having described the construction of my 65 fraud preventive for coin controlled vending machines, I will now proceed to a brief description of the operation thereof. When,

as before stated, a coin or disk of a smaller diameter than is necessary to operate the machine is inserted in the entrance opening 2, it falls from the guideway 8 into the chute 15 which is connected to the main discharge chute 32. Supposing the machine to be designed to operate when a five cent piece is deposited in the slot 2 and such a coin is used. The nickel will drop from the guideway 8 through an opening 8' on to the jaws of the levers 16 and 17. The plunger 20 is then forced inwardly which causes the upper wall of the opening 25 to engage the rounded lug 30 and force the arm 29 against the coin and knock the latter from between the levers on to the slide 34. The spring 44 holds the kicker lever normally against the plunger 20. From the slide 34 the nickel passes on to the tilting platform 35, causing said platform to swing into a vertical plane and drop the nickel into the chute 3. The spurs 40 engage the inner sides of the flange of the nickel so that the latter does not drop from the platform until the same is directly over the chute 3. If the nickel is old and worn, it slides from the platform into the chute 33 and, if an iron disk or slug is used in place of a nickel, it will have its hold upon the platform loosened by the magnet 42 and will slide into the chute 33 and be returned to the depositor. Should a check or any other article having a central opening be deposited in the slot 2 it will be caught by the levers 16 and 17 in the same way as the coin as just described, but a different operation takes place when the plunger 20 is forced inwardly. The arm 29 of the kicker lever 27 passes through the opening in the check and does not knock the latter on to the slide 34. The inward movement of the plunger opens the jaws of the levers 16 and 17 so as to leave the check unsupported except by the arm 29 and when the lug 30 is opposite the opening 26, the kicker lever 27 swings back into its normal position, allowing the check to drop into the chute 31 and be returned to the depositor. If a disk of tinfoil or other soft material is forced into the slot 2, it will be flattened by the plunger 45 and either drop from the guideway 8 when it reaches the cutaway portion 14, or pass between the jaws of the levers 16 and 17 directly into the chute 31.

From the foregoing description taken in connection with the accompanying drawings, it will be evident that I have provided a very simple and highly efficient fraud preventing device for coin controlled vending machines, which will effectually prevent such machines being fraudulently operated by spurious coins, slugs and in fact any but the proper legal coin.

While I have shown and described the preferred embodiment of my invention, it

will be understood that minor changes in construction, combination and arrangement of parts may be made without departing from the scope and spirit of the invention as claimed.

Having thus described my invention, I claim:

1. In a coin controlled vending machine, an inclined coin guideway, a pair of pivoted levers to support a coin or similar article as it passes from the guideway, a pivoted kicker lever to knock a coin or similar article from between said levers, a plunger for actuating the kicker lever, means actuated by the plunger for spreading said levers, the kicker lever passing through an apertured article without disturbing its position and then allowing said article to drop between the spread supporting levers.

2. In a coin controlled machine, a coin guideway which discharges a coin in a substantially vertical plane, a pair of pivoted levers between which a coin discharged from the guideway is supported, a pivoted kicker lever, means for actuating the kicker lever to kick a coin laterally from between said pivoted levers, and means for spreading the jaws of the pivoted levers at each operation of the kicker lever, whereby an article not dislodged by contact of the kicker lever is released.

In testimony whereof I affix my signature in presence of two witnesses:

HARRY J. SWEANY.
